CHARLES A. BOGERT, OF BAY CITY, MICHIGAN.

Letters Patent No. 88,839; dated April 13, 1869.

IMPROVEMENT IN KNIFE-SHARPENERS.

The Schedule referred to in these Letters Patent and making part of the same.

To all whom it may concern:

Be it known that I, CHARLES A. BOGERT, of Bay City, in the county of Bay, and State of Michigan, have invented a new and useful Implement for Sharpening Knives and other like edge-tools or implements; and I hereby declare that the following is a full, clear, and exact description of the construction and operation of the same, reference being had to the annexed drawings, making a part of this specification, in which—

Figure 1 is a perspective view of one side, and

Figure 2, a like perspective view of the reverse side.

The mode of construction is as follows:

First, a piece of steel, capable of bearing a high degree of temper, and of a suitable thickness, is cut out, of such size and shape as may be desired, having reference to the size of the sharpener to be made.

Second, an opening is then drilled or punched through the piece of steel, at a convenient distance from the end or edge of the same, as represented by the drawings, Nos. 1 and 2, accompanying this application.

Third, from this opening to the end or edge of the piece of steel, a cut is made in the shape of a double V, and so bevelled as to be open on one side, and, after being made perfectly smooth and sharp on the other side, it is brought together, so that the sharp edges, or

jaws of the V, are closed up or slightly lapped at the bottom, and as far up from the bottom as may be desired.

Fourth, it is then tempered to such a degree of hardness that the sharp edges are capable of smoothly cutting away or shaving off the sides of a blade of a knife, or other tool or implement, which it may be desirable to sharpen, in such a manner as to produce a sharp edge.

Fifth, the cutting part of the V may be formed of jewels, firmly fixed or set in the steel or other metal, of which the body of the instrument is composed, the form and shape as above being retained.

Sixth, the mode of using this sharpener is by placing the edge of the knife or other implement to be sharpened in the opening, and drawing it through the V, from the closed toward the open side thereof.

What I claim as my invention, and desire to secure by Letters Patent, is—

The knife-sharpener, constructed as herein described, and for the purpose specified.

CHARLES A. BOGERT.
